UNITED STATES PATENT OFFICE.

JAMES C. GEYER, OF NAPPANEE, INDIANA.

HEADLIGHT DIMMER.

Application filed January 13, 1926. Serial No. 80,920.

My invention relates to automobile head-lights and especially to means for eliminating the glare of the head-light.

- The principal object of my invention is 5 to provide an improved hood, or dimmer element, to eliminate the glare of the head-lights of an automobile, and also means to enable the ready application of the device to the standard type of head-light.
- 10 Another object of the invention resides in the provision of readily attachable clamping bands adapted to carry the dimmer hood and the bearings for the hood actuating shaft.
- 15 A third object of the invention resides in the provision of readily attachable clamping bands adapted to carry the dimmer hood, the bearings for the hood actuating shaft, and means to conceal the band clamping 20 means to render the device more artistic in appearance.

Other objects of the invention are mentioned and described herein.

- The preferred embodiment of my invention is illustrated in the accompanying drawing in which Figure 1 is a side elevation of an auto head-light showing my improved dimmer mounted thereon; Fig. 2 is a front elevation of an automobile illustrating the 25 application of my invention to the head-lights thereof; Fig. 3 is a top plan view of one of the dimmer hoods and the actuating elements connected therewith; Fig. 4 is a fragment of one of the hood carrier bands 30 showing one shaft bearing element applied thereto; Fig. 5 is a view of the same element at right angles thereto; and Fig. 6 is a section taken on line 6—6 of Fig. 4.

Similar numerals of reference indicate 40 like parts throughout the several views on the drawing.

Referring to the details of the drawing, the numeral 1 indicates an automobile fragment provided with the two spaced head-lights 2, 2 suitably mounted upon brackets 3, 3 secured in the frame of the car in the usual manner, which said brackets may be connected by a transverse rod 4 to steady the lamp unit.

50 The invention herein contemplates a glare eliminating hood or dimmer 5 carried by each of the lamps 2 and movably mounted upon a split clamping band 6 which is readily attachable to and removable from each lamp, as hereinafter described, together with 55 means operative from the auto dash for si-

multaneously actuating said dimmer hoods. In Fig. 1 of the drawing the normal position of the hood 5 is indicated by the full lines thereof, and the dotted lines thereof indicate 60 the depressed or glare eliminating position thereof. Both hoods 5, and the two bands 6, respectively, are of similar construction and a description of one of each will suffice.

Each band 6 is preferably made of sheet or 65 strap metal and divided, and formed circularly to encompass the cylindrical body of the lamp 2, the division point of the band being provided with integral end lugs 7 and 8 in which the clamping screw 9 is 70 mounted. The outer end of band lug 8 is extended at 10 and downwardly, at right angles, to cooperate with lug 7, to partially conceal the screw 9. The arch-like hood 5 is tiltably arranged above the band 6 and is 75 provided with a pair of spaced hinge lugs 11 which are hingedly connected with corresponding hinge lugs 12 rigidly connected with the band 6 and projecting forwardly 80 therefrom above the divided portion of the band. And each hood 5 is provided with a single arm 13 extending laterally from one side thereof and adapted to pivotally carry the forward end of the actuating link 14, the other end of said link being pivotally connected with the outer end the lever arm 15 85 at 16, said lever arm being rigidly secured to the horizontally arranged rock-shaft 17 which extends transversely of the car front and between the lamps 2 and is journaled at 90 its opposite ends in the bearing eye 18 of the element 19. The bearing element 19 is secured to the upper face of the band lug 8 by the head of the screw 9 and is provided with the extension 20 which is right angularly 95 bent downward to cooperate with the band lug 7 and the lug extension 10, to effect complete concealment of the screw 9, Fig. 6.

The numeral 21 indicates a coil tension spring the lower end whereof is anchored in 100 the rod 4, the upper end thereof being connected with the arm 15, adjacent the outer end thereof, to normally hold the hood 5 elevated. The numeral 22 indicates an arm depending from the rock-shaft 17 and rigid 105 therewith with which a link 23 is connected, the latter extending rearwardly toward the dash of the car and having its rear end connected with the lever 24 pivotally mounted at 25 in the dash and manually operable and movable within the slot 26 of the guide element 27 also rigidly secured in the car dash.

Obviously, the full line position of the hood 5, as illustrated in Fig. 1 of the drawing, effects the full and un-dimmed light ray from the lamp. To dim the light the car driver tilts the hand lever 24 to the dotted line position thereof, as illustrated in Fig. 1, thereby depressing the front end of the hood 5 to the dotted line position thereof. Upon release of the lever 24 the coil spring 21 retracts the parts to the original, or full line, position thereof, said lever engaging the end wall of the slot 26 which serves as a stop therefor.

I claim:

15 The combination with a vehicle head-light, of a divided band encompassing said head-light, said band being provided with a pair of spaced clamping lugs, one of said lugs being extended angularly to cooperate

with the other, screw means for clamping 20 said band about said head-light said screw means being mounted in said band lugs, a dimmer hood tiltably mounted upon said band, a rock-shaft, a rock-shaft bearing element carried by one of said band lugs and 25 provided with an angular extension adapted to cooperate with said band lug extension to conceal the screw of said band clamping means, actuating devices connecting said dimmer hood and rock-shaft, and means connected with said rock-shaft and operable from the vehicle dash for controlling the movement of said shaft and thereby said dimmer hood.

In witness whereof I have hereunto affixed 35 my signature this 8th day of January, 1926.

JAMES C. GEYER.
